UNITED STATES PATENT OFFICE.

WILLIAM C. WINFIELD, OF WARREN, OHIO, ASSIGNOR OF TWO-THIRDS
TO ROLLIN A. COBB AND ORRIS R. GRIMMESEY, OF SAME PLACE.

PRESSURE-BLOWER.

SPECIFICATION forming part of Letters Patent No. 355,111, dated December 28, 1886.

Application filed April 3, 1886. Serial No. 197,675. (No model.)

To all whom it may concern:

Be it known that I, WILLIAM C. WINFIELD, of Warren, in the county of Trumbull and State of Ohio, have invented certain new and 5 useful Improvements in Pressure-Blowers; and I do hereby declare the following to be a full, clear, and exact description of the invention, such as will enable others skilled in the art to which it pertains to make and use the same.

10 My invention relates to improvements in pressure-blowers, in which the piston is located in the pressure-chamber, and the inverted rims, respectively, of the piston and of the tank inclosing the pressure-chamber are fluid-sealed 15 in a sealing-chamber, the latter being formed by upwardly-projecting walls that below are joined to a head in common, the space inclosed by the inner wall forming an induction air-chamber, to the end that the device is rendered 20 more compact and convenient and is made at a less initial cost than pressure-blowers heretofore in use.

In the accompanying drawing the figure is a side elevation of my improved pressure-blower, parts being broken away to show the internal construction.

The body of the blower consists of a conical head, A, to which are joined the upwardly-projecting walls A' and A'', the space between 30 these walls forming a sealing-chamber, A''', in which respectively operate and are fluid-sealed the downwardly-projecting rims B' and C', respectively, of the tank B and piston C. Both tank and piston have preferably conical heads, 35 as shown, to give the necessary stiffness and strength to enable them to withstand the internal pressure. The tank B incloses the pressure-chamber B'.

The parts thus far described are usually 40 made of sheet metal, thicker or thinner, according to the size of the blower.

The head A is provided with a valve, a, and the head of the piston C with a valve, c, both valves opening upward. A piston-rod, 45 D, passes through the apex of the head A, where it may be provided with a stuffing-box, a'. The piston-rod at c' is joined to the center of the piston-head, as shown.

It will be seen that the piston-rod is operated from below, and the piston being located

inside the tank B, as aforesaid, requires no extra room.

Heretofore with pressure-blowers the tank B, or whatever served as an equivalent, was usually placed in a separate sealing-chamber, 55 container, or whatever the arrangement might have been, thereby requiring about double the space occupied by my improved blower, the latter, therefore, being made at a greatly-reduced initial cost. A discharging-pipe, E, 60 leads from the inside of the pressure-chamber, and preferably through the sealing-chamber, and in such case the wall A'' and rim C' are usually curved, as shown, so as to make room for the pipe. The exact location of the pipe 65 is not, however, essential, and might, if preferred, be made in two parts, the one part extending up through the head A inside the induction-chamber, and the other part secured to and extending through the head of the piston, the two parts of the pipe being arranged in line, and the end of one pipe operating inside of the other pipe, forming a slip-joint. There would be nothing gained by such construction, and as a slip-joint is somewhat objectionable, the construction shown is considered 75 preferable.

The piston-rod extending below is usually an advantage, especially as would be the case with small blowers operated by foot-power, 80 as a treadle for operating the blower could be attached to the floor. The device as shown is believed to be in the most compact and desirable form attainable, and can be made at a comparatively small initial cost. 85

What I claim is—

1. In a pressure-blower, the combination, with a head having the upwardly-projecting walls A' A'', located a sufficient distance apart to form a sealing-chamber, of the piston, the 90 lower end of which rests within the sealing-chamber, and the tank closed at its upper end and open at its lower end, and inclosing said piston, the lower end of said tank also resting within the sealing-chamber. 95

2. In a pressure-blower, the combination, with the body of the blower, the same consisting of inner and outer walls joined below to a head in common, forming sealing and induction chambers, as indicated, of a piston and 100

tank, the former located in the pressure-chamber of the latter, both tank and piston having depending rims operating and fluid-sealed in the same sealing-chamber, substantially as set forth.

3. In a pressure-blower, the combination, with inner and outer upright walls joined below to a head in common, said walls inclosing a sealing-chamber, and the inner walls inclosing an induction-chamber, of a piston and tank, the former located inside the pressure-chamber of the latter, both tank and piston having depending rims operating and fluid-sealed in the said sealing-chamber, a valve in the piston-head, a valve in the head A, and a discharging-pipe leading from the pressure-chamber and preferably through the sealing-chamber, substantially as set forth.

4. The combination, with the body of the blower, the same consisting of inner and outer walls joined below to a head in common, forming sealing and induction chambers, of a piston and tank, the former located in the pressure-

chamber of the latter, and both tank and piston operating and fluid-sealed in the same sealing-chamber, and a piston-rod extending down through the induction-chamber, substantially as set forth.

5. In a pressure-blower, the combination, with the body of the blower, the same consisting of inner and outer walls joined below to a head in common, forming sealing and induction chambers, of a piston and tank, the former located in the pressure-chamber of the latter, both tank and piston having depending rims operating and fluid-sealed in the same sealing-chamber, and the discharge-pipe passing downwardly through the said sealing-chamber, substantially as set forth.

In testimony whereof I sign this specification, in the presence of two witnesses, this 26th day of March, 1886.

WILLIAM C. WINFIELD.
